(57) **CLAIM**

We claim the ornamental design for a lighting device charger, as shown and described.

DESCRIPTION

FIG. 1 is a right top perspective view of the lighting device charger of the present invention.

FIG. 2 is a front view of the lighting device charger of the present invention.

FIG. 3 is a back side view of the lighting device charger of the present invention.

FIG. 4 is a right side view of the lighting device charger of the present invention.

FIG. 5 is a left side view of the lighting device charger of the present invention.

FIG. 6 is a top view of the lighting device charger of the present invention; and,

FIG. 7 is a bottom view of the lighting device charger of the present invention.

The broken line showing is included for the purpose of illustrating environmental features and forms no part of the claimed design.
